UNITED STATES PATENT OFFICE.

DONALD MCK. HEPBURN, OF AKRON, OHIO, ASSIGNOR TO HEPBURN DECARBONIZER COMPANY, OF NEW YORK, N. Y., A CORPORATION OF NEW YORK.

DECARBONIZING VALVE FOR INTERNAL-COMBUSTION ENGINES.

1,405,843.

Specification of Letters Patent. Patented Feb. 7, 1922.

Application filed February 19, 1918. Serial No. 218,116.

To all whom it may concern:

Be it known that I, DONALD MCK. HEPBURN, a citizen of the United States, residing at Akron, in the county of Summit and State 5 of Ohio, have invented certain new and useful Improvements in Decarbonizing Valves for Internal-Combustion Engines, whereof the following is a specification, reference being had to the accompanying drawings.

10 My invention relates to a valve to be applied to an internal combustion engine, and which is adapted to receive and measure a quantity of a liquid decarbonizer and to transfer said decarbonizer to the cylinder 15 while under pressure. To this end my decarbonizing cup comprises a casing fitted with a hollow measuring cylinder. The casing has a funneled entrance and also a discharge aperture leading to the cylinder. 20 The hollow cylinder has non-opposed apertures capable of communicating the one with the funneled entrance and the other with the discharge aperture. These apertures are so related that when the funneled entrance is 25 opened, the discharge aperture is closed, and vice versa. It is also so arranged that at no intermediate point between the two positions can pressure from the cylinder escape and blow through the valve. The hollow cylinder 30 is completely closed except for its apertures above spoken of, and its hollow interior is of a size to measure a proper charge of the decarbonizing liquid. The interior is of such shape as to permit its contents to completely drain out through the discharge aperture. 35

In order that the turning of the valve may be effective to accomplish its purpose no matter in which direction it is turned, I find 40 it well to provide two discharge apertures one or the other of which will come into service according to which way the valve is turned.

In the accompanying drawings, Fig. I, is 45 a plan view of a decarbonizing valve involving my invention.

Fig. II, is a view of the cylinder and Fig. III of its washer.

Fig. IV, is a vertical sectional view 50 through the decarbonizing valve.

Figs. V, VI, and VII are cross sectional views along the line V, V, of Fig. IV, showing the valve in three different positions.

The casing 1, is preferably an integral casting which is in the shape of a truncated cone, with its interior forming a ground joint to receive the cylinder 10. Upon the upper side of the casing is a funneled entrance 2, communicating with the interior of the cup by the longitudinal slot 3. Upon 60 the opposite or lower side of the casing is a discharge aperture 4 directly through its wall, communicating with a discharge tube 5, the threaded end 6, of which is capable of being screwed into engagement with the cylinder to which the device is attached.

Upon the discharge tube 5, is formed the polygonal nut 7, which enables the device to be screwed to the cylinder without the necessity of subjecting the functional parts of the 70 valve and casing to any torsional strain which would be liable to disturb the accurate adjustment of the parts.

The cylinder 10, is preferably formed as a single hollow casting. Its outer surface 75 forms a ground joint registering accurately with the interior surface of the casing 1. The interior of the cylinder is barrel-shaped the sides sloping from both ends towards the central region in which the discharge 80 aperture is situated. The interior of the cylinder is of such capacity as to be capable of measuring off the desired charge of decarbonizing liquid, and the sloping sides ensure the complete draining of the same 85 when turned to its position of discharge.

The hollow cylinder is provided with a slotted aperture 14, capable of registering with the corresponding aperture 3, of the casing, and also with another aperture 15 (for discharge) directly through its wall, capable of registering with the discharge aperture 4. It may also preferably be provided with a second discharge aperture 16 directly through its wall, which is also capable of 95 registering with the aperture 4, provided the cylinder be turned in the opposite direction.

The larger end of the hollow cylinder has attached to it a handle 18, which is prefer- 100

ably longer upon one side than the other, so as to the more conspicuously indicate the position of the valve. The smaller end of the cylinder is prolonged in the form of a stem 20, with a partially flattened shoulder 21, the remainder 22, being screw threaded for the reception of the rounded nut 23.

A special washer 25, is interposed between the end of the casing and its nut. Internally the washer is provided with a flattened surface 26, capable of engaging the flattened shoulder 21. It is also provided with a recess 28, for the reception of a coiled spring 29, which exerts pressure against the nut 23, to maintain the washer firmly against its seat. The washer has a ground annular surface 30, which fits against the annular end of the casing.

The exposed larger end of the hollow cylinder is provided with marks, not shown in the drawing, which are capable of registering with corresponding marks on the larger end of the casing, to indicate the various positions to which the cylinder must be turned in order to perform its successive function; or, in place of such marks, suitable stops may be provided.

In operation the valve is turned initially to the position of Fig. V, in which the slotted aperture of the hollow cylinder registers with the funneled entrance, and in this position a measured charge of decarbonizing liquid is poured in. The funnel greatly assists in this operation, while the elongated 35 slotted aperture is useful to permit the simultaneous entrance of the decarbonizing liquid and the exit of the air thus displaced. In this position it will be noted that the hollow interior of the cylinder is not in communication with anything but the entrance. By the rotation of the hollow cylinder to the position shown in Fig. VI, the entrance is closed and the exit opened by the registry of aperture 15, with aperture 4, in which 45 position the measured charge is free to discharge itself straight through the valve wall directly into the cylinder, notwithstanding pressure therein which cannot escape because of the otherwise complete closure of 50 the interior of the cylinder. In passing from the position of Fig. V, to that of Fig. VI, there is an intermediate position shown in Fig. VII, in which the interior of the cylinder is completely closed, in which position the measured charge may be maintained as long as desired before allowing it to pass into the cylinder.

Depending upon the position of the valve in relation to the cylinder to which it is attached, it may be more convenient in operation to turn the cylinder to one side or the other, and in order that the valve may operate equally well no matter which way it is turned, the second aperture 16, is provided

enabling it to discharge itself when turned 65 in the opposite direction from that shown in Fig. VI.

The ground annular joint between the annular surface 30, of the washer, and the annular end of the casing, is the only gas or 70 vapor-tight joint formed upon the washer. Accordingly if gas escapes from the exit 4, to the smaller end of the hollow cylinder, it readily finds its way out between the surface of the washer on one side, and those of 75 the stem and its rounded nut. The provision of such escape is desirable for the reason that a tapered cylindrical ground joint, such as is employed in my device, tends to wear toward the small end. Gas passing in 80 that direction if not otherwise free to escape, will force the cylinder slightly out of its casing, in order that it may thus escape. Such action is prevented by the washer which I have described.

Having thus described my invention, I claim:

1. A decarbonizing valve comprising a cylindrical casing member and a closed hollow valve member rotatable therein; said casing 90 and valve members having entrance and discharge openings for the reception of liquid and discharge thereof to an engine cylinder, and said valve member being otherwise completely closed; the entrance and discharge 95 openings of said valve member being capable of successive, but not concurrent, registration with those of said casing; and the entrance afforded by registration of valve and casing entrance openings being elongated, so 100 as effectually to vent the valve interior of air.

2. A decarbonizing valve comprising a casing member with an entrance opening for the reception of fluid and a discharge opening for delivery thereof to an engine cylinder; and a closed hollow valve member rotatable in said casing and having entrance and discharge openings directly through its wall 105 capable of successive, but not concurrent, registration with those of said casing, said discharge openings when in register thus affording a direct discharge straight through the wall of the valve member.

3. A decarbonizing valve comprising a 115 casing member having a funneled entrance and an elongated entrance opening, and also a discharge opening for delivering to an engine cylinder; and a closed hollow valve member rotatable in said casing and having corresponding entrance and discharge openings capable of successive, but not concurrent, registration with those of said casing.

4. In a decarbonizing valve, the combination of a casing and a hollow cylinder therein, said parts being of truncated cone shape with opposing ground surfaces, and having entrance and exit apertures, and said cyl-

inder having an axial screw-threaded stem at its smaller end; a nut on said threaded stem; a spiral spring beneath said nut; and a washer on said stem having a ground joint 5 with the end of the casing and a central recess enclosing said spring and affording an abutment therefor.

In testimony whereof, I have hereunto signed my name at Philadelphia, Pennsylvania, this sixteenth day of February, 1918. 10
DONALD McK. HEPBURN.
